TRANSLUCENT LIGHT SHIELD

Thomas E. Kiernan, Newburgh, N. Y., assignor to
 E. I. du Pont de Nemours & Company, Wil-
 mington, Del., a corporation of Delaware

Application December 24, 1937, Serial No. 181,565

2 Claims. (Cl. 156—24)

This invention relates to the art of window shading and more particularly to a double roller shade and light shield assembly.

There are many drawbacks to the common window shade arrangement wherein one shade mounted on a roller is used to shade an entire window. The window cannot be opened at the roller end without causing drafts which quickly injure and destroy the curtain. Even with perfect operation, it is not possible to shade a portion of the window except that adjacent the roller. This is a serious hindrance to the use of this type of construction, especially in school rooms, offices, and the like, where it is often desired to shade only the bottom or the top of a window at a given time. Other disadvantages are known to the general public.

The commonest way of overcoming these difficulties is to mount two shade rollers medially on the window frame, and open them in opposite directions so that one will shade the lower half and the other the upper half of the window. This arrangement also has disadvantages. If the shades are arranged in such a way that they overlap in unwinding from their respective rollers, light enters at the sides of the shade which is suspended away from the window. Furthermore, this same shade rubs on the other in operation and as a result is quickly frayed and worn out. If both shades unwind toward the window (in an effort to avoid the last-mentioned detriments) a gap or slit is left between the rollers. This allows light to enter the room when complete shading is desired.

To overcome this disadvantage, it has been proposed that a shield be placed either in front of or behind the opening between the two rollers. These proposals do not solve the problem either commercially or esthetically. Such constructions are expensive (often costing more than the roller shades themselves) and do not blend well with the interior decoration. An opaque light shield (such as that known to the prior art) detracts from the inherent beauty of a translucent window shade arrangement because of too great a contrast with that portion of the window admitting light. In addition, the operation is not satisfactory because opaque shields shade a portion of the room even when shading is not wanted. This is as undesirable as having a slit of light when shading is desired. Furthermore, they leave a dark blot across the window and a disagreeable bar of shadow across the room when a mild-light shading is desired. Even a large window shade dealer could not be expected to

stock opaque light shields in all window sizes and in all the colors and patterns common to translucent shades.

Some reduction in cost may have been obtained by making the shield of wood and covering it with shade cloth. The device of this patent, while presenting a fairly satisfactory color scheme, does not overcome the disadvantages of opaqueness. The shield is opaque and the wood center is located at the very place where translucency is desired. It also requires a special bracket, which adds materially to the cost. 10

This invention had for an object the provision of an inexpensive, esthetically desirable, translucent light shield. Further objects were 15 to provide a light shield readily installable on any sized window, to provide a light shield in a pattern which harmonizes with the window shade material mounted on the spring rollers, and to provide a light shield not requiring special supporting brackets. A general advance in the art and other objects which will appear hereinafter are also contemplated. 20

It has now been found that a translucent light shield may be prepared by turning over the edges 25 of a strip of material from which the window shades are constructed and stitching this turned-over portion to form pockets in which reinforcing elements are later inserted. In operation the resulting assembly is mounted behind the brackets 30 used for supporting the window shade rollers. By such an arrangement the light shield is mounted in a taut or extended condition without the necessity of special brackets or external reinforcing elements. 35

From the following description and specific examples in which are disclosed certain embodiments of the invention as well as details of what is believed to be the best mode for carrying out the invention, it will be apparent how the foregoing objects and related ends are accomplished. 40 The written description is amplified by the accompanying drawing, in which:

Figure 1 is a view representing somewhat diagrammatically, with parts broken away, an assembly comprising a window frame, upper and lower window shades, and a translucent light shield mounted behind the window shade rollers; 45

Figures 2 and 3 are views representing some- 50 what diagrammatically the brackets (together with the light shield) used to support the window shade rollers and maintain the light shield in position;

Figure 4 is a view representing somewhat dia-

grammatically a stock roll of the light shield materials; and

Figure 5 is a view representing somewhat diagrammatically a translucent light shield ready for installation.

Figure 6 is a view representing somewhat diagrammatically the bracket arm which supports the gudgeon end of a window shade.

Similar reference characters refer to similar parts throughout the drawing.

In securing a mode detailed idea of the invention, it will be convenient to refer to the drawing in which the light shield in general is represented by the numeral 11. The shield comprises a rectangular translucent portion, having pockets extending lengthwise along its edges. The opposed pockets are ordinarily identical in construction and are indicated in the drawing by the numeral 12. In its operative form the light shield has reinforcing rods indicated at 13 inserted in the aforementioned pockets. These rods are preferably circular in cross section but may in special circumstances, if desired, have annular, irregular or geometrical outlines, for example, squares, triangles, trapezoids or other polygons. In order to obtain a pleasing appearance with the light shield when it is in operative position, the reinforcing rods must have considerable structural rigidity. For this reason, coupled with price consideration, iron or steel rods are preferred. With due consideration for appearance and the aforementioned characteristics, rods of aluminum, aluminum alloys, magnesium alloys, and like materials may be employed. If desired the rods may be galvanized or given other surface treatments, such as non-ferrous metal plating (for example, cadmium or nickel), to prevent corrosion.

In commercial practice the manufacturer of light shade (and shield) material prepares the light shield stock in rolls, such as that illustrated in Figure 4, and sells it to the window shade dealer, who cuts the shields in proper lengths, inserts the stiffening rods, and installs the light shield (usually at the time the window shades are being installed). The light shield stock is prepared by folding over the edges of material (window shade) of appropriate width and stitching the same as indicated at 14. Cementing or stapling may, on occasion, replace or supplement the stitching. It is then rolled to prepare it for convenience in handling and shipping.

The light shields may be made of any translucent material which suits the user. Because of the long life and satisfactory resistance to wear and cleaning, it is preferred that the shields be made of a pyroxylin coated fabric which is well known as a window shade material. The preparation of such sheet material is not a part of this invention, but for completeness of disclosure reference is made to U. S. Patents 1,951,119, issued March 13, 1934, and 2,033,170, issued March 10, 1936, which describe in detail its production. The material of U. S. patent application No. 55,198, filed December 19, 1935, now Patent No. 2,127,320, issued August 16, 1938, is particularly suitable for window shades and light shields. Pyroxylin coated paper has also been found suitable. The production of such a material is disclosed in U. S. patent application No. 110,298, filed November 11, 1936, now Patent No. 2,156,046, issued April 25, 1939.

Further reference is made to the drawing in Figure 1 wherein the numeral 20 represents

somewhat diagrammatically a window frame, against which is mounted the light shield 11 by means of the brackets 17 and 18. The brackets also support the upper and lower window shades 15 and 16, respectively. The upper window shade is raised or lowered by means of a cord 151, operating over a pulley 152 in the well known manner. Similarly, the lower shade is raised or lowered by means of a cord 161. In Figure 1, the shade rolls 153 and 163 are broken 10 away at the left in order to show more clearly the manner in which the light shield 11 is mounted behind the bracket 17. The bracket 17 is held against the window frame by means of screws or similar fasteners 171. The bracket 18 is similarly attached. These screws go through the light shield which is positioned between the bracket and the window frame. The light shield, as will now be clear, is maintained in position in three ways. The screws which hold the 20 brackets in place extend through the light shield; they also hold the brackets in such a way that they (the brackets) clamp the light shield against the window frame, and the reinforcing rods (through the light shield material) bear 25 on the upper and lower edges of the brackets.

The brackets 17 and 18 are of conventional construction and are usually manufactured in pairs. In Figure 2 the bracket 17 is illustrated 30 in detail. It comprises an upper supporting arm 172 having a circular opening 176, surrounded by a raised bead or edge 177 adapted to receive and serve as a bearing for the free end of the shade roller. The bracket also has a lower arm 173 having an offset slot 178 adapted to receive 35 the fixed end of the window shade roller. An embossed or raised portion also surrounds this opening. The embossed portion has circular openings on opposite sides of the gudgeon receiving slot, as indicated at 174. These holes are adapted to receive a cotter pin or key, as illustrated at 19 in Figure 6. The cotter pin prevents the pintle-like gudgeon end of the window shade roller from slipping out of the slot 178 during operation, especially when an upward pull is exerted on the shade. Both upper and lower arms of this bracket may have circular openings indicated at 175, adapted to receive fastening means.

In Figure 3 the bracket 18 is illustrated more 50 in detail. In this bracket the receiving arm for the gudgeon end of the shade is at the top, and is indicated by the numeral 183. An embossed portion 189 containing cotter pin holes, indicated at 184, is ordinarily utilized. As was the case with bracket 17, the bracket 18 has a revolving pintle receiving circular opening 186, surrounded by an annular pressed out ring 187. These are located in the lower arm 182. The openings for side fastening are indicated at 185.

It has been found that an over-all height of 4 1/4 inches for the brackets 17 and 18 is suitable for most installations. It has also been found that steel rods 1/4 inch in diameter are exceptionally well adapted for use as stiffening means 13. 65 This combination of dimensions calls for a light shield having an over-all width or height of approximately 4 3/4 inches.

Ordinarily the pockets on the side of the light shield are formed in a continuous manner, that 70 is to say, the fabric base is cut into continuous lengths and thereafter the longitudinal edges are continuously folded over and continuously stitched to form the pockets as shown at 121 in Figure 4. Having the pockets in this flat form

facilitates a rolling or coiling of the material as it leaves the stitching machine.

The pressure which the brackets 17 and 18 apply to the ends of the light shield in clamping it to the window frame serves to keep the light shield stretched width-wise on the window. A similar stretching at right angles is provided by the stiffening rods 13 which press against the ends of the brackets. The top part of the light shield preferably extends beyond the top part 5 of top roller 153, and the bottom part of the light shield preferably extends below the bottom part 10 of the bottom roller 153. This overlap which ordinarily is very slight may be more or less as desired.

The operation of the window shades is conventional. When it is desired to shade the upper portion of the window the cord 151 is pulled over the pulley 152, raising the shade 15. A conventional type of pulley 152 provides for the clamping of cord 151 in any position. When this type of pulley is utilized the gudgeon end of the top roller 153 ordinarily is not pawl-locked, since the cord 151 positions the window shade.

By this invention there is produced for the first time a translucent light shield having the same appearance as the window shades whose action it supplements. This enables the user to obtain complete harmony of color and light transmission value, and in addition to its desirable esthetic features and pleasing eye value

it has the advantage of being inexpensive and easy to install. It may easily be produced at a cost which is only a fraction of that of the shields known to the prior art. As will be apparent from the foregoing description, the light shield may 5 (without an expensive stocking of material) be readily installed on windows of any size by the dealer, the person best fitted to meet the demands of a specific shading situation.

As many apparently widely different embodiments of this invention may be made without departing from the spirit and scope thereof, it is to be understood that I do not limit myself to the specific embodiments thereof except as defined in the appended claims.

I claim:

1. In a window shade assembly having a window frame, rollers and a support mounted centrally across said window frame, translucent shades mounted on said rollers which unwind in 20 opposite directions with a space between said rollers, the improvement which comprises a light shield of translucent material having essentially the same degree of translucency as said shades, said shield overlying said space between said 25 rollers, whereby the light passing between said rollers is screened.

2. The assembly of claim 1 in which the light shield has a metal frame at its perimeter and a cellulose derivative coated fabric is stretched tightly about the frame.

THOMAS E. KIERNAN.
